CLAIM

The ornamental design for a bag for carrying in-line skates and accessories, as shown and described.

DESCRIPTION

FIG. 1 is a front perspective view of the bag carrying in-line skates and accessories showing my new design;

FIG. 2 is a rear elevation view thereof;

FIG. 3 is a right side elevation view thereof;

FIG. 4 is a top plan view thereof;

FIG. 5 is front elevation view thereof;

FIG. 6 is a left side elevation view thereof; and,

FIG. 7 is a bottom plan view thereof.

The broken line showing of environment in FIGS. 1-7 is for illustrative purposes only and forms no part of the claimed design.
